[57] CLAIM

The ornamental design for a stand for supporting an ice bucket, pot, vase or similar article, substantially as shown and described.

DESCRIPTION

FIG. 1 is a reduced perspective view of the stand for supporting an ice bucket, pot, vase or similar article illustrating my new design;

FIG. 2 is a top plan view of FIG. 1; and

FIG. 3 is a cross-sectional view taken substantially along the line 3—3 of FIG. 1.
